UNITED STATES PATENT OFFICE

DAVID PERLMAN, OF NEW ORLEANS, LOUISIANA

FOUR-CYLINDER, FOUR-CYCLE CAM AND LEVER RADIAL MOTOR

Application filed April 29, 1929. Serial No. 359,135.

The present invention relates to improvements in mechanical movements, and more particularly refers to a mechanical movement applied to an internal combustion or other engine.

An object of the invention is to provide an engine of light weight, great power, low speed crank shaft and producing great leverage and power.

10 With the foregoing and other objects in view, the invention will be more fully described hereinafter, and will be more particularly pointed out in the claims appended hereto.

15 In the drawings, wherein like symbols refer to like or corresponding parts throughout the several views,

The figure is a plan view of an engine constructed according to the present invention.

20 Referring more particularly to the drawings, 1 designates the drive or main shaft, which is journaled in bearings 2 of any appropriate character.

25 The valve cam disk is indicated at 3, having thereon the intake cams 4 and the exhaust cams 5.

30 A circular cam or cam wheel 6 is also made fast on the shaft 1. On this cam disk 6 are cams 7 engaged by rollers 9 carried upon the intermediate parts of levers 8. Pins 10 connect the rollers 9 to the levers 8. Links 11 connect the intermediate portions of adjacent levers 8 together, the pins 10 being utilized for connecting the links to the levers. 35 Piston rods or other rods 13 are coupled to the levers 8 at one end, as by the pins 12. Other pins 14 at the opposite ends of the levers 8 pivotally secure the levers 8 to ribs 16 extending inwardly from the housing 15. The connecting rods 13 are, of course, coupled to the pistons which operate in the cylinders, the pistons and the cylinders being conventionally shown.

40 In operation, the explosions occur in the engine cylinder in the usual manner, and through the connecting rods 13, levers 8 and rollers 9 reacting on the cams 7, the cam disk 6 and the shaft 1 are thus made to rotate. The small cams 4 and 5 are also rotated to operate the valve assembly in a well-

known manner. The links 11 connect the rollers of adjacent levers and keep the rollers continuously riding the cam disk.

The improved device eliminates the necessity of valve timing gears, and creates three working strokes per cylinder per revolution. By means of the lever principle, the pressure exerted by the piston thrust through the center of the lever on the cam disk, by means of the roller, to the drive shaft is increased approximately fifty per cent or more. Also due to this cam and lever arrangement, the hammering effect of the piston thrust is reduced. The firing order being in rotation, considerable vibration is eliminated. As a result of the increased number of power impulses in one revolution upon the drive shaft, the drive shaft speed also is greatly reduced. The motor will have more impulses and power than any four cylinder motor of radial design having equal cylinder dimensions and specifications. The ribs 16, being integral with the housing, tend to strengthen the same. The weight per horse power is also greatly reduced.

Having thus described the invention, what is claimed is:

1. In a mechanical movement, cylinders radially arranged, pistons therein, levers having one end secured to fixed fulcrums, and the other end coupled to the pistons, a main shaft, a cam wheel fixed to said main shaft and acted on by the intermediate portions of the levers, and links for connecting the intermediate portions of the levers together.

2. In a mechanical movement, a rotary element, a reciprocating element, a connecting rod pivoted at one end to the reciprocating element, a lever pivoted at one end to the other end of the connecting rod, said lever having a fixed fulcrum at its opposite end, a roller offset toward the rotary element from the intermediate part of the lever, and a circular cam fixed to the rotary element and having rounded pockets of a size to receive the roller and convex high points between the pockets also to engage said roller.

DAVID PERLMAN. 100
